UNITED STATES PATENT OFFICE.

HENRY ANDERSON, OF SUMNER, WASHINGTON, ASSIGNOR OF ONE-HALF TO
S. SAMPSON, OF TACOMA, WASHINGTON.

DESIGN FOR A REIN GUARD AND HOLDER.

SPECIFICATION forming part of Design No. 29,514, dated October 18, 1898.

Application filed September 20, 1898. Serial No. 691,456. Term of patent 14 years.

To all whom it may concern:

Be it known that I, HENRY ANDERSON, a citizen of the United States, residing at Sumner, in the county of Pierce and State of Washington, have invented and produced a new and original Design for a Rein Guard and Holder, of which the following is a specification.

This invention relates to a new and original design for a combined rein guard and holder; and it has for its object to provide a new and original design of this character that shall be both useful and ornamental.

The leading feature of the design resides in a straight semitubular bar provided at each end with a right-angularly-disposed upstanding arm and within the concaved side thereof with a longitudinally-arranged wire body joined at one end to the bar and having its other end curved or deflected outwardly, said semitubular bar being further provided at its front convexed side and centrally between its ends with a horizontally-arranged offset substantially rectangular loop.

The minor features of the design are the upstanding arms at the ends of the semitubular bar, each having a lateral offset eye at its upper extremity and at an intermediate point, and the wire body within the concaved side of the bar having separate parallel strands provided with coiled extremities joined to the bar.

In the drawings, Figure 1 is a perspective view of the obverse side of a combined rein guard and holder embodying the herein-described design. Fig. 2 is a similar view of the reverse side of the combined guard and holder. Fig. 3 is a rear elevation thereof.

Referring to the accompanying drawings, the numeral 1 designates a straight semitubular bar of a **U** shape in cross-section and 40 provided at its opposite extremities with right-angularly-disposed upstanding arms 2. The oppositely-located upstanding arms 2 at the ends of the bar are arranged parallel with relation to each other, and each of said arms 45 is provided at its upper extremity and at an intermediate point with a lateral offset eye 3. At its rear side and within the concavity thereof of the said semitubular bar 1 is further provided with a longitudinally-arranged wire 50 body 4, extending nearly the entire length thereof and having separate parallel strands 5, which are provided at one end with coiled extremities 6, joined to the bar. At its end opposite the connection of the strands 5 with 55 the bar the said wire body 4 is provided with a looped end 7, which is curved or deflected outwardly.

An additional feature of the design is the semitubular bar being provided on the outer 60 convexed side thereof and centrally between its ends with an offstanding horizontally-arranged rectangular loop 8.

What is claimed is—

The design for a combined rein guard and 65 holder, herein shown and described.

In testimony that I claim the foregoing as my own I have hereto affixed my signature in the presence of two witnesses.

^{his}
HENRY X ANDERSON.
